UNITED STATES PATENT OFFICE.

WINFIELD E. MCINTYRE, OF SYRACUSE, NEW YORK.

PAPER-MAKING MACHINE.

1,149,379.

Specification of Letters Patent. Patented Aug. 10, 1915.

Application filed July 5, 1913. Serial No. 777,406.

To all whom it may concern:

Be it known that I, WINFIELD E. MCINTYRE, a citizen of the United States, residing at Syracuse, in the county of Onondaga and State of New York, have invented certain new and useful Improvements in Paper-Making Machines, of which the following is a specification.

This invention relates to improvements in paper machines, and has particular relation to the type of machines which make tissue and other thin papers.

The primary object of the invention is to prevent the newly formed web of tissue or like thin paper from sticking to the press-rolls, which frequently causes the breaking of the paper and otherwise interferes with the rapid and perfect manufacture of the same.

20 A further object is to provide a novel and simple construction and arrangement of the press-rolls, in combination with a separator-roll, whereby the paper is carried directly from the felt to the separator-roll and thence to the first drier. And a further object is to simplify and reduce the number of working parts, whereby less power is required to operate the paper forming machinery.

25 The features and parts of the invention will be understood from the detailed description which follows and by reference to the accompanying drawing, in which the figure is a side elevation of a paper machine 30 of the cylinder type, to which my improvement is applied.

In the drawing, 2 represents a vat which contains the liquid pulp, in which is disposed a perforated or wire-cloth cylinder mold 3, 40 upon which the layer of pulp is first formed.

44 4 represents the usual couch-roll, which is disposed above and bears upon the cylinders 3.

45 5 and 6 represent the press-rolls, both of which are preferably covered with rubber, although any suitable metal may be employed for the purpose. The roll 5 is supported by a frame 7 in the usual way, and is driven by a shaft 8 by means of a pair of 50 miter-gears 9 and 9'. The roll 6 is disposed directly above and bears upon the roll 5, and is held in place by a half-bearing 10, which is movable vertically in, and is guided by brackets 11 which are supported by the 55 frame 7. The roll 6 is pressed against the roll 5 for giving the required tension for

squeezing the water out of the pulp, by a spring 12 which is controlled by a rod 13, which is rotated by a hand-wheel 14.

15 represents a third press or separator 60 roll, which contacts with the roll 6, and which is supported at each end by levers 16, which are pivoted at one end, as at 17, to the brackets 11. The roll 15 is preferably held tightly against the roll 6 by a tension 65 device, which comprises a rod 18, the upper end of which connects with lever 16, while the lower end is pivoted at 19 to a lever 20.

One end of lever 20 is pivoted to the frame 7 by a pin 21, the opposite end of 70 lever 20 carries a weight 22, which is adjustable on said lever for increasing and decreasing the tension on the roll 15.

The rod 18 is in two sections and is adjustable by means of a turn-buckle 23. 75

The layer of pulp which is formed on the cylinder 3, is taken therefrom by a felt apron or belt 24, which passes between said cylinder and the couch-roll 4, thence part-way around the roll 4, thence between the 80 press-rolls 5 and 6. The felt 24 then passes downwardly and back to the forward end of the machine, and in so doing is supported and guided by a series of idler and tension rolls 25, and a pair of squeeze-rolls 26. 85

27 represents a second felt apron or belt, which also passes between the rolls 5 and 6 and thence partially around the roll 6, which drives the said belt, the roll 6 being driven by friction by the roll 5. The felt 27 90 is carried and guided through the upper frame portion 28, by means of a series of idler and tension rolls 29. The web or layer of pulp, as it passes between the rolls 5 and 6, to which it is carried by the felt 24, is 95 taken from said felt by the felt 27, and carried part-way around the roll 6 and between said roll and the roll 15. The layer of pulp then clings to the roll 15 until it reaches a point marked 30, from which the pulp or paper 31 passes to and over a guide roller 32, and from said roller the paper passes directly to the first drier 33, without the aid of any felt. The arrows throughout the drawing indicate the directions in which the 100 various parts travel in doing their work.

Just before the upper felt 27 reaches the roll 6, it passes over a box 35, in which is disposed a whipper 36, which is driven by a belt 37. The whipper is of the usual construction, having a number of bars 38, which beat against the felt, thereby loosening up 110

and brushing off dirt and particles of pulp, which if allowed to remain on the felt produce imperfections in the layer of pulp which forms the paper. After the felt travels over the whipper it passes between squeeze-rolls 39 and 39', and then over a suction-box 40 which sucks the water therefrom. The lower felt 24 is treated substantially in the same manner by a whipper 41 and the squeeze-rolls 26.

By the provision and arrangement of the press-rolls 5 and 6, each having an independent felt apron between which the new layer of paper is carried, and by which practically all of the water is squeezed out of the pulp, in connection with the separator-roll 15, which takes the damp web of paper from the felt 27, I am able to carry or run the paper direct from the roll 15 to the first drier 33 without the aid of any felt. By this arrangement several extra couch and squeeze rolls and also other parts are eliminated, so that I am able to operate the rolls 5, 6 and 15 and also the two felts by a single drive comprising the shaft 8 and the gears 9 and 9'. This effects a considerable saving in the power, and in addition greatly simplifies and cheapens the construction of the working parts of the machine. Any desired tension may be applied to the roll 15, but I prefer only to use enough pressure to enable the said roll to pick up and carry the web or layer of damp paper away from the belt 27.

Heretofore, practically all of the pressing of the layers of tissue paper has been done by press rolls corresponding to the rolls 5 and 6, in connection with a single felt, with the result that the paper adheres too tightly to the bare upper roll 6, which prevents its free delivery to the driers, and which frequently causes the paper to break. But by the employment of the two felts 24 and 27, practically all of the pressing is done between the said felts by the rolls 5 and 6, and there is little danger of the paper sticking to the roll 15, tightly enough to tear or break the layer, and I am therefore able to operate my machine for intervals of weeks at a time without having any breaks in the paper. In practice the upper felt 27 is a heavy closely woven belt, while the lower

felt 24 is lighter and more openly woven, which allows the water to pass through the said felt. By this arrangement, the paper readily follows the upper felt, and is also readily taken from said felt by the roll 15, which delivers the paper to the first drier, as described.

Having thus described my invention, what I claim as new and desire to secure by Letters Patent, is—

1. In a machine for making tissue paper, the combination with a cylinder, a couch roll, a pair of press rolls, and a drier, of a pair of felts, one of the felts passing between the couch roll and cylinder and carrying the paper between the press rolls, the second felt also passing between the press rolls, and a separate roll bearing directly against the felt upon one of the press rolls at a decreased pressure from that at which the press rolls are held in contact, said second felt serving to carry the paper from between the press rolls to the said separator roll.

2. A machine for making tissue paper, comprising a vat, a cylinder in said vat, a couch roll meshing with said cylinder, a pair of press rolls; a drier, and a pair of felts, one of the felts passing between the couch roll and cylinder, and carrying the paper between the press rolls, and the second felt also passing between the press rolls, of a separator roll bearing directly against the felt upon one of the press rolls, means for holding the said separator roll pressed against the felt upon said press roll at a pressure less than the pressure at which the press rolls are held together, and means for maintaining the second felt drier than the other felt so that the former serves to carry the paper between the press rolls to the separator roll, said separator roll being frictionally driven by the said press roll through the engagement of the separator roll with the said felt and press roll, substantially as and for the described purpose.

In testimony whereof I affix my signature in presence of two witnesses.

WINFIELD E. MCINTYRE.
